UNITED STATES PATENT OFFICE.

JAMES H. DYETT, OF BUFFALO, NEW YORK, ASSIGNOR TO HARD MANUFACTURING CO., OF BUFFALO, NEW YORK.

DESIGN FOR A COUCH.

Application filed April 23, 1926. Serial No. 17,417. Term of patent 3½ years.

To all whom it may concern:

Be it known that I, JAMES H. DYETT, a citizen of the United States, residing at Buffalo, in the county of Erie and State of New York, have invented a new, original, and ornamental Design for Couches, of which the following is a specification, reference being had to the accompanying drawing, forming a part thereof.

The figure is a perspective view of a couch showing my new design.

I claim:

The ornamental design for a couch, as shown.

JAMES H. DYETT.
